Primary Examiner — Doris Clark

(57) **CLAIM**

The ornamental design for a microphone acoustic enclosure, as shown and described.

DESCRIPTION

FIG. 1 is a perspective view of a microphone acoustic enclosure showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 2.
